BRICK AND TILE MACHINE

Filed Sept. 11, 1930

UNITED STATES PATENT OFFICE

ALEXIS PRESTON STEELE, OF STATESVILLE, NORTH CAROLINA

BRICK AND TILE MACHINE

Application filed September 11, 1930. Serial No. 481,264.

This invention relates to brick and tile machines, and it is an object of the invention to provide a bearing or shaft support which will effectively carry and position the shaft and at the same time allow for the desired continuous travel of the material along the shaft and beyond the bearing.

Another object of the invention is to provide a bearing or shaft support which is constructed in a manner to minimize resistance offered to the travel of the damp clay.

An additional object of the invention is to provide a bearing or shaft support comprising a member rotatable with the shaft and which member is provided with means to facilitate the desired travel of the material toward the barrel so that the bearing or shaft support offers no undue hindrance or obstruction to the required travel of such material.

The invention consists in the details of construction and in the combination and arrangement of the several parts of my improved brick and tile machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view in side elevation of a combined brick and tile machine constructed in accordance with an embodiment of my invention;

Figure 2 is a fragmentary view partly in section and partly in side elevation particularly illustrating the bearing or shaft support as herein disclosed;

Figure 3 is a sectional view taken substantially on the line 3—3 of Figure 2;

Figure 4 is a fragmentary view partly in section and partly in elevation illustrating the mounting for a roller as herein embodied.

As disclosed in the accompanying drawings, B denotes the barrel of a straight line combined machine which substantially con-

stitutes a continuation of a pug tub T. Disposed axially of the barrel B and substantially centrally through the tub T is a shaft 1, said shaft extending on through for power application and thrust load in a manner particularly illustrated in my copending application Serial No. 290,222, filed July 3, 1928, wherein said shaft 1 is coupled to the power source or driving means by a flexible connection.

The opposed ends of the barrel B and the tub T have interposed therebetween a connecting frame F comprising two separable sections one superimposed upon the other, but tied or connected through the instrumentality of the bolts 2 or the like. Each section of the frame F comprises the side members 3 tied or connected at desired points by the cross members 4 whereby said side members 3 are maintained in desired spaced relation.

The lower section of the frame F is bolted or otherwise secured, as at 5, to the suitably positioned outstanding flanges 6 arranged at the opposed end portions of the barrel B and tub T.

Between adjacent cross members 4 the side members 3 of the sections of the frame F are provided with the transversely aligned open slots 7 radially disposed with respect to the axial center of the frame F and in each pair of aligned slots 7 is snugly received the end portions of a shaft 8. The opposite end portions of the shaft 8 are flattened, as at 9, for direct contact with the side walls of the associated slots 7 whereby the shaft 8 is held against rotation but permitted to have movement lengthwise of the slots 7 so that the position of the shaft 8 with respect to the axial center of the frame F may be adjusted as desired.

As particularly illustrated in Figure 4, each of the side members 3 inwardly of a slot 7 has inserted therethrough an angular extension 10 carried by the inner end portion of an elongated rod 11. This rod 11 extends outwardly and radially with respect to the frame F and is freely disposed through an end portion of a shaft 8. The rod 11 outwardly of the associated end portion of the shaft 8 has threaded thereon an adjustable

stop or nut 12 limiting the extent of outward movement of the shaft 8.

Each end portion of the shaft 8 has threaded therethrough an elongated shank 14 for contact with the inner face wall of the slot 7. These shanks 14 provide means whereby the inward movement of the shaft 8 may be readily regulated or controlled.

Mounted on the portion of the shaft 1 with-
10 in the frame F for rotation therewith is a hub
15 from which radiates the spokes 16 which
constitute knives connecting the hub 15 with
the rim 17. The spokes or knives 16 are dis-
15 posed on a hand or pitch to assure effective
feed of the material, such as the damped
clay, from the pug tub to the barrel.

The periphery of the rim 17 is defined by
the oppositely disposed flanges 18 and closely
approaching the opposite faces of the rim 17
20 are the annular members or liners 19, the in-
ner faces of which being provided there-
across with the ribs 20. These members or
liners 19 operate to prevent excessive leakage
25 or passage of clay out through the frame F
while the ribs 20 coat with the clay or ma-
terial in a manner to maintain the portion
thereof with which the knives or spokes 16
are coacting substantially against rotation
whereby the desired travel or feed of the clay
30 is assured. Contacting with the periphery
of the rim 17 and its flanges 18 are the rollers
21 rotatably arranged on the shafts 8 and
which provide an effective support for the
shaft 1 and to maintain the forward portion
35 of the shaft 1 in proper position.

It is to be noted that the rim 17 is extremely
narrow with the spokes or knives 16 ex-
tending beyond opposite sides thereof. This
is of advantage in that the rim offers no
40 hindrance or obstruction to the desired pas-
sage of the clay or material and minimizes
the liability of rotary action being imparted
to the clay or material. It is also believed
to be self-evident that as the shaft 1 rotates
45 the knives or spokes 16 cut through the ma-
terial.

It is also believed to be apparent that the
upper section of the frame F can be readily
removed when desired by releasing the con-
50 nection, as at 2, and that the frame provides
what may be termed a "self-containing rig-
ging" which can be stationed or positioned at
any desired location to carry or support the
shaft. However, it is particularly desirable,
55 as before stated, to have this frame F posi-
tioned or interposed between the pug tub T
and the barrel B.

The members or liners 19 are snugly ar-
ranged within the central portion of the
60 frame F and held thereto by the bolts 22 or
the like. These bolts, as particularly illus-
trated in Figure 4, are directed through the
transversely disposed slots 23 provided in the
members or liners 19 whereby said liners may
65 be readily adjusted with respect to the rim

17 as the requirements of practice may ne-
cessitate.

From the foregoing description it is
thought to be obvious that a brick and tile
70 machine constructed in accordance with my
invention is particularly well adapted for
use by reason of the convenience and facility
with which it may be assembled and operated,
and it will also be obvious that my invention
75 is susceptible of some change and modifica-
tion without departing from the principles
and spirit thereof and for this reason I do
not wish to be understood as limiting myself
to the precise arrangement and formation of
80 the several parts herein shown in carrying out
my invention in practice except as herein-
after claimed.

I claim:—

1. In combination with a shaft of a brick
and tile machine, a rim surrounding said
85 shaft and disposed intermediate the ends
thereof, spokes operatively connecting the
rim and the shaft, said spokes constituting
knives, and supporting means rotatably en-
gaging the rim.

2. In combination with a shaft of a brick
and tile machine, a rim surrounding said
95 shaft and disposed intermediate the ends
thereof, spokes operatively connecting the
rim and the shaft and disposed in angular
relation to the axis thereof, said spokes con-
stituting knives, and supporting means in
50 rolling engagement with the rim.

3. In combination with a shaft of a brick
and tile machine, a rim surrounding said
100 shaft and disposed intermediate the ends
thereof, spokes operatively connecting the
rim and the shaft, a casing about the rim
and shaft and supporting means carried by
the casing and engaging the rim, said spokes
105 constituting a feeding medium to convey
material through the rim.

4. In combination with the pug tub, bar-
rel and shaft of a straight line combined
brick and tile machine, a frame, a rim sur-
rounding the shaft and disposed within the
frame between the pug tub and barrel and
110 rotating with the shaft, supporting means
for the shaft coacting with the rim, and
means coacting with the rim to substantially
eliminate the passage of material there-
beyond.

5. In combination with the pug tub, bar-
rel and shaft of a straight line combined
brick and tile machine, a frame, a rim sur-
rounding the shaft and disposed within the
frame between the pug tub and barrel and
115 rotating with the shaft, supporting means
for the shaft coacting with the rim, members
bridging the spaces between the rim and the
tub and the barrel to prevent passage of
material beyond the rim.

6. In combination with the pug tub, barrel
and shaft of a straight line combined brick
and tile machine, a frame, a rim surround-
120

the shaft and disposed within the frame between the pug tub and barrel and rotating with the shaft, supporting means for the shaft coacting with the rim, members bridging the spaces between the rim and the tub and the barrel to prevent passage of material beyond the rim, said members being continuous and provided with transverse ribs on their inner faces to hold the material passing

10 through the rim against rotation.

7. In combination with the tub and barrel of a combined brick and tile machine, a shaft common to both the tub and barrel, a frame interposed between the tub and barrel, spokes 15 extending outwardly from the shaft within the frame, a rim operatively engaged with the spokes, said spokes constituting knives, and members carried by the frame and coacting with the rim to rotatably support the

20 shaft.

8. In combination with the tub and barrel of a combined brick and tile machine, a shaft common to both the tub and barrel, a frame interposed between the tub and barrel, spokes 25 extending outwardly from the shaft within the frame, a rim operatively engaged with the spokes, said spokes constituting knives, and members carried by the frame and coacting with the rim to rotatably support the

30 shaft, said spokes also providing means to carry material through the rim and frame.

In testimony whereof I hereunto affix my signature.

ALEXIS P. STEELE.
